Inventor:

A. J. Tewksbury

UNITED STATES PATENT OFFICE.

A. J. TEWKSBURY, OF HAVERHILL, MASSACHUSETTS.

LAST-BLOCK FASTENING.

Specification forming part of Letters Patent No. 44,352, dated September 20, 1864.

To all whom it may concern:

Be it known that I, A. J. TEWKSBURY, of Haverhill, in the county of Essex and Commonwealth of Massachusetts, have invented a new and useful Last-Block Fastening; and I do hereby declare that the following is a full and exact description thereof, reference being had to the accompanying drawing, and to the letters of reference marked thereon.

The nature of my invention consists, first, in furnishing the piece of metal A, which is fastened to the block B by means of a screw, f, which acts as a hinge, and the piece of metal C of the last D go together with a dovetail joint, as hereinafter described, and prevents the block from lifting up; second, in the use of a piece of metal, E, fastened to the block B, and follows in a groove in the last D, which prevents the top from moving sidewise.

To enable others skilled in the art to make and use my invention, I will proceed to describe its construction and operation.

A is a piece of metal fastened to the block B by means of a screw, f, which acts as a

hinge, and under the top is a coiled spring, as hereinafter described.

C is a piece of metal made fast to the last D, with a slot in it, which forms a part of the dovetail joint.

Now place your thumb on the top part of A and press it in, and that will throw out the bottom part out of the slot in C. Now the block is free and can be drawn back from the last D. Now, to fasten the block B to the last D, shove down the block so E will enter the groove in the last D, and the coil-spring will throw A into the slot C, which fastens the block B and last D firmly together.

What I claim as my invention, and desire to secure by Letters Patent, is—

The dovetail joint A and C, in combination with the screw f, which acts as a hinge, substantially as set forth, and for the purpose specified.

A. J. TEWKSBURY.
